US0D1065759S

(12) **United States Design Patent** (10) Patent No.: **US D1,065,759 S**
(45) Date of Patent: ** Mar. 11, 2025

(54) **ROOT VEGETABLE PRODUCT**

(71) Applicant: **McCain Foods Limited**,
Florenceville-Bristol (CA)

(72) Inventors: **Wei Zhang**, Shanghai (CN); **Xiaogang Wu**, Harbin (CN); **Chenglong Li**, Harbin (CN)

(73) Assignee: **McCain Foods Limited**,
Florenceville-Bristol (CA)

(**) Term: **15 Years**

(21) Appl. No.: **29/916,210**

(22) Filed: **Nov. 9, 2023**

(51) LOC (15) Cl. **01-01**

(52) U.S. Cl.

USPC **D1/125**; D1/199

(58) **Field of Classification Search**

USPC D1/100–130, 199; D7/504, 509, 510,
D7/523, 524, 555, 566, 568, 584–587,

(57) **CLAIM**

The ornamental design for a root vegetable product, as shown and described.

DESCRIPTION

FIG. 1 is a top perspective view of a root vegetable product in accordance with a first embodiment of our Design;

FIG. 2 is a front view thereof;

FIG. 3 is a rear view thereof;

FIG. 4 is a left side view thereof;

FIG. 5 is a right view thereof;

FIG. 6 is a top plan view thereof;

FIG. 7 is a bottom plan view thereof;

FIG. 8 is a top perspective view of a root vegetable product in accordance with a second embodiment of our Design;

FIG. 9 is a front view thereof;

FIG. 10 is a rear view thereof;

FIG. 11 is a left side view thereof;

FIG. 12 is a right view thereof;

FIG. 13 is a top plan view thereof;

FIG. 14 is a bottom plan view thereof;

FIG. 15 is a top perspective view of a root vegetable product in accordance with a third embodiment of our Design;

FIG. 16 is a front view thereof;

FIG. 17 is a rear view thereof;

FIG. 18 is a left side view thereof;

FIG. 19 is a right view thereof;

FIG. 20 is a top plan view thereof; and,

FIG. 21 is a bottom plan view thereof.
